UNITED STATES PATENT OFFICE.

CARL M. MANOR AND JOHN MILLER, OF CLEVELAND, OHIO.

AUTOMOBILE-SIGNAL.

1,283,844.

Specification of Letters Patent.

Patented Nov. 5, 1918.

Application filed April 23, 1917. Serial No. 164,028.

To all whom it may concern:

Be it known that we, CARL M. MANOR and JOHN MILLER, citizens of the United States, residents of Cleveland, county of Cuyahoga, and State of Ohio, have invented new and useful Improvements in Automobile-Signals, of which the following is a specification, the principle of the invention being herein explained and the best mode in which 10 we have contemplated applying that principle, so as to distinguish it from other inventions.

Our invention relates to signal devices and particularly to that class of such devices 15 which is adapted for use upon automobiles. More particularly, our invention relates to automobile signals which are adapted to be manually operated transversely of the machine by the driver thereof so as to display 20 outside of the machine and upon the proper side thereof the necessary signal.

The annexed drawings and the following description set forth in detail certain means embodying our invention, the disclosed 25 means, however, constituting but one of various mechanical forms in which the principle of the invention may be employed.

In said annexed drawings:

Figure 1 represents, looking from the 30 driver's position, an elevation of our improved signal applied to an open type of automobile, and in the operative position; Fig. 2 represents an enlarged elevation of a spear-shaped signal member and a broken 35 elevation of a tube member supporting the same; Fig. 3 represents a plan view and horizontal section taken in the plane indicated by the lines III—III, Fig. 1; Fig. 4 represents a vertical section taken in the 40 plane indicated by the lines IV—IV, Fig. 1, showing the automatically locked operative position of the signal-operating members; Fig. 5 represents an enlarged view of fragmentary portions shown in Fig. 3; Fig. 45 6 represents an enlarged vertical section taken in the plane indicated by the lines VI—VI, Fig. 2; Fig. 7 represents an enlarged view of some details shown in Fig. 6; Fig. 8 represents an enlarged vertical section 50 taken in the plane indicated by the lines VIII—VIII, Fig. 1; Fig. 9 represents an enlarged broken horizontal section taken in the plane indicated by the lines IX—IX, Fig. 1; Fig. 10 represents a front elevation

of our improved signal when used outside 55 of an automobile in a closed type of car; Fig. 11 represents a vertical section taken in the plane indicated by the lines XI—XI in Fig. 10; Fig. 12 represents an enlarged elevation of a bracket attached to the body of 60 the car within easy reach of the driver, when the type of signal adapted to a closed type of car is being used, the purpose of said bracket being hereinafter fully explained; Fig. 13 represents an enlarged broken vertical section taken in the plane indicated by the lines XIII—XIII, Fig. 12; Fig. 14 represents an enlarged plan view and horizontal section taken in the plane indicated by the lines XIV—XIV, Fig. 12; Fig. 15 represents an enlarged view of a clamp adapted 70 for use as a part of our improved signal upon a closed type of car; Fig. 16 represents an enlarged broken vertical section taken in the plane indicated by the lines XVI—XVI, Fig. 10, and Figs. 17, 18 and 19 represent details of our invention, the same being combination blocks and pulleys and wood screws used with a closed type of car. 75

Referring to the annexed drawings, an 80 automobile body is indicated at 1 to which is secured in any approved manner the usual wind-shield 2. Our improved signal is designed to be supported by the automobile body 1 adjacently to said wind-shield and 85 rearwardly of the same in an open type of car and forwardly thereof in a closed type of car. Referring now particularly to the type of signal adaptable for use with an open car, there are shown in Figs. 1, 3 and 90 5, brackets 3 supported upon the automobile body, the same being a portion of the means supporting the wind-shield, one of said brackets laterally of each end of the wind-shield, and to this bracket there is secured 95 within suitable clamps 4 a tube member 5 disposed transversely of the automobile body and extending laterally thereof upon each side. Secured to each end of this tube member is a shield or casing 6 for signal device 100 7, as plainly shown in Figs. 1 and 3. These signal devices 7 are carried each upon the outer end of an inner tube member 8 disposed within the tube member 5 in each end thereof and movable longitudinally thereof. 105 The outer tube member 5 is provided with two longitudinally disposed grooves 9 and the inner tube members 8 are provided with

diametrically opposed holes 10. A hand member 11 mounted upon the outer end of a pin 12, which pin intersects the groove 9 and the holes 10, effects the longitudinal movement of the tube member 8. When the hand member 11 has moved the tube member 8 to its outermost position to display the signal device 7 in its operative position, the pin 12 intersects a depression 13 in the outer tube member 5 disposed diametrically opposite the groove 9, such positive movement of the pin 12 being effected by a spring 14, so that the inner tube member 8 and the signal device 7 are thus automatically locked in their operative position. When it is desired to make the signal device 7 inoperative by pulling the same back into the shield 6, the hand member 11 is pulled outwardly from the tube member 5 to pull the pin 12 out of the depression 13 and then a spring 15 secured to the pin 12, as plainly shown in Figs. 1 and 4, forces the pin 12 and the inner tube member 8 and consequently the signal device 7 back into inoperative position.

25 The signal device is provided with red glass or any other suitable danger design and, when it is desired to use the device at night, or if it is desired to use a lamp at any other time, a suitable bulb 16 and suitable wiring 30 17 are provided, as plainly shown in Fig. 1, a switch being provided for throwing on or off the current. The circuit is made or broken during the actuation of the device or operative or inoperative positions by 35 means of contact points 19 and 20 provided upon the casing 6 and inner tube 8, respectively.

Referring now to the type of device adapted for use with a closed car, Fig. 10, the 40 transversely disposed tube 5 is located forwardly of the wind-shield and there are no depressions 13 provided in said tube member. The inner tube members 8 in this form of device are actuated as follows: Rearwardly of the wind-shield and suitably secured to the automobile body is a bracket 21, Figs. 10 and 12, provided with a pair of slides 22 within which are adapted to move a pair of hand operated members 23 to which 45 are respectively connected a pair of cables 24. The outer tube member 5 of this form of device is supported by a pair of clamps 25 suitably secured to the automobile body, as plainly shown in Fig. 10. The hand member 11 and pin 12 intersecting the longitudinal groove 9 and holes 10 of the outer and inner tube members 5 and 8, respectively, have secured to them, the other ends of the cables 24, as plainly shown in Fig. 11. It 55 60 is apparent that the actuation of the hand members 23 in the slides 22 will effect, respectively, the movements to operative and inoperative positions of the signal device 7. Referring now particularly to Fig. 13, it

will be noted that the hand member 23 is intersected by a pin 26 provided with a head 27 disposed within the extension 29 of said member 23 and adjacently to a spring 28 secured to the bracket 21. Said extension 29 is secured to block 31 secured to the cable 24. The spring 28 is provided with an angular end member 30 adapted, when the hand member 23 is pulled downwardly, to intersect a depression 29' of the extension 29 to hold said extension and, consequently, 75 the cable 24, tube member 8 and signal device 7 in operative position. When it is desired to release the signal member, the same is effected by pushing the pin 26 in through the hand member 23 so that the head 27 will 80 contact with the spring 28 and push the angular end 30 of the same out of the depression 29' and thus release the hand member 23, the spring 28 pulling the pin 26 and consequently the inner tube member 8 and 85 the signal device 7 to their inoperative positions.

What we claim is:

1. In an automobile signal, the combination with the automobile body and wind-shield; of a pair of brackets supported by said body and disposed laterally of said wind-shield and at each end thereof; a pair of clamps supported by said brackets respectively; a tube member having a pair of longitudinal grooves and a pair of depressions and disposed transversely of the automobile and supported in said clamps; a pair of tube members slidably disposed in said first mentioned tube member and in each end thereof; signal devices carried at the outer ends of said pair of tube members; a pair of hand-operated members movable in said longitudinal grooves, respectively, and intersecting said inner tube members, respectively, to effect the movement of the latter; springs tending to hold said hand members in their innermost positions, said hand members in their outermost positions being adapted to intersect said depressions and to be retained thereby; and means automatically effecting said retained positions of said members.

2. In an automobile signal, the combination with the automobile body and wind-shield; of a pair of clamps attached to the sides of the car, respectively, and contiguous to, and forwardly of, said wind-shields; a tube member supported by said clamps transversely of the car; a pair of inner tube members slidably retained in the ends, respectively, of said first-mentioned tube member; signal devices supported upon the outer ends, respectively, of said inner tube members; a bracket supported by the body of the car adjacently the driver's position; a pair of slides in said bracket; a pair of cables connected, respectively, at one end to said inner

tube members; a pair of hand-operated members adapted to be moved in said slides, respectively, the other ends of said cables, respectively, being connected to said members; means adapted automatically to retain said members in that position designed to display

the signal devices; and means tending to move said members into the other extreme position in said slides.

Signed by us, this 20th day of April, 1917.

CARL M. MANOR.

JOHN MILLER.
